UNITED STATES PATENT OFFICE.

HEINRICH DECHAMPS, OF CHARLOTTENBURG, GERMANY, ASSIGNEE TO GENERAL ELECTRIC COMPANY, A CORPORATION OF NEW YORK.

FUEL-PUMP FOR INTERNAL-COMBUSTION ENGINES

1,165,855.

Specification of Letters Patent. Patented Dec. 28, 1915.

Application filed March 14, 1913. Serial No. 754,257.

To all whom it may concern:

Be it known that I, HEINRICH DECHAMPS, a subject of the King of Prussia, residing at Charlottenburg, Germany, have invented 5 certain new and useful Improvements in Fuel-Pumps for Internal-Combustion Engines, of which the following is a specification.

The present invention relates to pumps 10 for supplying liquid fuel to internal combustion engines, and more especially to pumps for supplying fuel to high compression engines wherein a charge of air is compressed to a temperature above the igniting temperature of the fuel and into 15 which the fuel is injected.

The object of my invention is to improve the construction and governing mechanism for such pumps, and for a consideration of 20 what I believe to be novel and my invention attention is directed to the accompanying description and claims appended thereto.

In the accompanying drawing is illustrated 25 one of the embodiments of my invention wherein,

Figure 1 is a longitudinal section of the pump taken in the plane of the pump; Fig. 2 is a detailed view in cross section of the 30 speed governor; Fig. 3 is a cross section of the pump taken in the plane of the eccentric which actuates the plungers; Fig. 4 is a section taken on the line 4—4 of Fig. 1; Fig. 5 is a horizontal sectional view taken 35 in a plane passing through the actuating means of the suction valves; Fig. 6 is a detailed view showing the arrangement of a suction valve lifter and its actuator; Fig. 7 is a similar view showing parts in a slightly 40 different position, and Fig. 8 is a perspective view of the crank shaft for adjusting the action of the suction valve actuator.

10 indicates the shaft for driving the fuel pumps, and the same shaft may be utilized 45 if desired to operate the cams controlling the admission of fuel to the engine cylinders. This shaft is located within a suitable housing 11 that is supported by the engine frame. Mounted on the shaft is a 50 driving gear 12 which receives its motion from gearing actuated by the main shaft of the engine. Mounted on the right-hand face of the gear and secured to it by bolts 55 is a support 13. Pivots mounted on the support are two weight arms 14 whose

outer ends move toward and away from the shaft as the speed changes. Each of the weight arms comprises a longitudinal member 15 having heads 16 at its ends to increase the mass thereof. Acting in opposition to the weights are two coiled extension springs 17 that are mounted in holders 18 which in turn are supported by caps 19 that engage the weights. The springs are arranged on opposite sides of the shaft so as to insure corresponding movements of 60 both weights and also to avoid any tendency thereof to twist.

The weight arms are made in the form of bell-crank levers 20 which are provided with pins 21 that engage shoulders formed on the sliding sleeve 22, the latter being arranged to move lengthwise on the shaft 10 as the speed of the engine changes under varying loads. On the right-hand end of the 70 sleeve are collars 23 that engage pins 24 carried by the bell-crank lever 25, the latter being supported by a pivot 26 carried by the housing 11. The long arm of the lever is provided with a fork which engages the pin 27 for the purpose of controlling the operation of the suction valves of the pumps, as will appear more fully hereinafter.

Mounted on the shaft 10 is an eccentric 85 28, and surrounding it is an eccentric strap 29 having a rod formed integral with its lower part. To the lower end of the rod is attached a slotted cross-head 30 of cylindrical form. The rod and cross-head are united by a pin 31, shown in dotted lines. 90 The lower end of the cross-head is provided with two side opening slots 32 in which are located the heads of the pump plungers 33. Each of these plungers is provided with two heads that engage the cross-head to prevent 95 independent movement thereof in the direction of their lengths. The plungers, however, are capable of moving slightly in a direction perpendicular to the axis of the cross-head to compensate for any inaccuracies in machine work. The guide 34 of the cross-head is formed in a casting that is secured to the housing by bolts 35. These bolts also serve to hold the casing 36 containing the pump cylinders in place.

The arrangement of the pump plungers 105 and cylinders is best shown in Fig. 4 wherein 33 indicates the plungers and 37 one of the cylinders. Each cylinder is provided with a suction valve 38 and a dis-

charge valve 39. The former is provided with a spring 40 which tends at all times to seat it. Fuel passing the discharge valve enters the conduit 41 from which it is conveyed to the fuel injector or pulverizer in the engine cylinder. Situated above the discharge valve is a screw-threaded plug 42 which when removed gives access to the valve and permits of its removal. Situated 10 in front of the heads of the plugs is a removable door 43 that is normally held in place by the spring pressed pins 44.

Prior to starting the engine it is sometimes necessary to fill the pipes between the 15 pump and the engine with fuel. To this end I provide a hand pump comprising a plunger 45 having a suitable handle and a spring 46 that tends to move the handle to the position shown. The plunger is mounted 20 in a screw-threaded plug, and the former is in line with the passage between the suction and discharge valves, so that said valves serve for the hand pump as well as the power pump.

25 The action of each pump is controlled by holding its suction valve off of its seat for a greater or less portion of the discharge stroke of the plunger 33. The portion of said stroke that the suction valve is held off 30 of its seat is determined by the load of the engine. The heavier the load, the shorter will be the portion of the stroke that the suction valve is held open. The means for accomplishing this result are as follows: 35 Each suction valve is provided with a depending stem that projects slightly below the bottom of the casing 36. Situated below the suction valves is a head 47 provided with adjustable stops 50 that under certain 40 conditions engage the stems of the suction valves and hold them off of their seats. The head 47 is mounted on a rod 51 that extends upward through the casing and terminates in a head 52. Between the head and the 45 casing is a spring 53 that tends at all times to raise the rod 51 and head 47 and open the suction valves. The head 47 is guided in its movements by the rod, and also by a guide pin 54 which enters an opening in the casing and also one in the cover 55 which surrounds the parts and forms a chamber to which fuel is admitted from any suitable source, as, for example, by the threaded nipple 56 and conduit connected therewith 55 as shown in Fig. 1. For convenience the parts 47, 50, 51, 52 and 53 may be termed a suction valve lifter.

The action on the lifter and the means for controlling it will now be described. 60 Mounted in suitable guides in back of the plungers is a crank-shaft 57, best shown in Fig. 8. On one end of the shaft is a crank-pin 58 which forms the adjustable fulcrum of the arm or actuator 59. By turning the 65 shaft 57 in one direction or the other, the

position of the fulcrum 58 will be changed to raise or lower the right-hand end of the actuator 59 and cause it to release the suction valves at an earlier or later portion of the plunger strokes. The actuator 59 is provided with a rounded end which engages a beveled cam face 60 on the crosshead 30, as shown in Figs. 4, 6 and 7, said cam being situated between the upper ends of the plungers. The bevel of the cam face 60 should be so selected that movements of the crank 58 change the point of contact between it and the actuator 59 but do not cause it to change the position of the head 52 in so doing. The beveled cam face or some equivalent device is necessary to permit of the longitudinal movement of the actuator as its fulcrum is angularly adjusted to raise or lower one end thereof. Arranging the actuator so that it crosses the top of the suction valve lifter and engages the cam face results in a simple construction and one occupying only a very small space. Furthermore the parts are simple in construction and can be easily and accurately made. As the fulcrum 58 of the actuator 59 is lowered, the portion of each plunger stroke that its suction valve is held off of its seat will be decreased, and hence the amount of fuel delivered to the engine will be greater. On the upward stroke of the plunger the suction valve will open due to the vacuum created thereby and also to the action of the spring 53. On the downward stroke of the plunger and crosshead 100 the latter will strike the actuator 59 and gradually force the suction valve lever downward until it releases the suction valves 38, and thereafter fuel displaced by the plungers 33 will be discharged through the 105 valves 39.

In order to transmit movements of the speed governor to the crank-shaft 57 a tubular member 61 is provided, Figs 1, 3, which is guided in a boss carried by the housing 110 11. Extending through the tubular member is a coiled compression spring 62 which is connected to the pin 27 at its upper end and to a pin 63 at its lower end which in turn engages the forked arm 64 that is rigidly mounted on the crank-shaft 57. By means of this arrangement, as the speed governor moves the sleeve 22 back and forth, motion is transmitted to the bell-crank lever 25, and through it to the arm 64 through 120 the spring and tubular member. This results in changing the position of the crank-pin 58, thereby causing the actuator 59 to engage the valve lifters at an earlier or later portion of the plunger strokes. As arranged 125 a downward movement of the tubular member 61 and arm 64, Figs 1 and 3, decreases the amount of fuel delivered by the pump by reason of the fact that such action increases the portion of the plunger stroke 130

that the suction valve is held open. Conversely, an upward movement of the member 61 and arm 64 increases the effective delivery of fuel.

5. It sometimes happens that it is necessary or desirable to shut down the engine quickly, on the one hand, or to insure maximum delivery of fuel to the engine, on the other, as in starting. To accomplish these results it 10 is necessary to provide a means for taking the control of the pumps away from the speed governor. I accomplish this in the present instance by providing a hand lever 65 which is loosely mounted on the crank- 15 shaft 57. It is provided with a spring latch 66 that engages a toothed sector 67, the latter being carried by a triangular frame 68 which is bolted to the back of the casing 36. This frame has a lateral extension 69, 20 Fig. 5, which forms a bearing for the shaft 57. As before stated the arm 64 is fast on the shaft and the handle 65 loose thereon. Between these parts are jaws 70 and 71 that are separated by relatively small spaces 72, 25 the whole forming a lost motion connection permitting the arm 64 to be moved by the governor without regard to the handle over a predetermined limited range. Assuming now that it is desired to shut down the en- 30 gine, the handle 65 is moved to its lowest position which first takes up the lost motion or space 72 and thereafter turns the crank- shaft 57 in the direction to move the actuator 59 to its extreme left-hand position, i. e., 35 where it will hold the suction valves off of their seats and hence no fuel can pass to the engine. This movement of the handle 65 is permitted by the spring 62 which flexibly connects the speed governor lever with the 40 arm 64. On the other hand, if a maximum supply of fuel is required the handle 65 is moved upwardly first taking up the lost motion and subsequently moving the actuator 59 to a position where it will release the 45 suction valves at the beginning of the plunger strokes or else to a position where it has no control whatever on said valves. The handle is normally set in some mid-position where it does not interfere with the 50 automatic action of the speed governor, and the spaces 72 should be calculated and arranged with this in view.

In accordance with the provisions of the patent statutes, I have described the principle of operation of my invention, together with the apparatus which I now consider to represent the best embodiment thereof; but I desire to have it understood that the apparatus shown is only illustrative and that 60 the invention can be carried out by other means.

What I claim as new and desire to secure by Letters Patent of the United States, is

1. In a pump, the combination of a cylin- 65 der, suction and discharge valves therefor,

a plunger, a member for actuating the plunger, said member being provided with a cam surface, a lifter for the suction valve, and an actuator for the lifter, said actuator being provided with an adjustable fulcrum 70 and having a free end which extends into the path of movement of the cam surface on said member.

2. In a pump, the combination of a cylinder, suction and discharge valves therefor, 75 a plunger, a cross-head for actuating the plunger, a lifter that always tends to raise the suction valve, an actuator for moving the lifter in a direction to release the valve, an adjustable fulcrum for the actuator, and 80 a cam carried by the cross-head which engages the free end of the actuator for moving it against the action of the lifter.

3. In a pump, the combination of a cylinder, suction and discharge valves therefor, 85 a plunger, a reciprocating cross-head to which the plunger is detachably secured, means for imparting movement to the cross-head, a cam face formed on the cross-head, an actuator, one end of which is located in 90 the path of travel of said cam, an adjustable fulcrum for the other end of the actuator, and a lifter for the suction valve which tends at all times to raise the valve from its seat, is located in the path of movement of 95 said actuator, and is moved thereby in a direction to release the valve and permit it to seat.

4. In a pump, the combination of a cylinder, suction and discharge valves therefor, 100 a cross-head, a plunger that is attached to the cross-head and is positively moved thereby, an eccentric and rod for reciprocating the cross-head, a cam face on the cross-head situated at one side of the plunger, an 105 actuator that is moved in one direction by the cam, an adjustable fulcrum for the actuator, and a lifter which tends at all times to hold the suction valve open and engages the actuator and holds it in engagement with the cam.

5. In a pump, the combination of a cylinder, suction and discharge valves therefor, a plunger, means for reciprocating it, a lifter for the suction valve biased to a position to 115 hold it open, an actuator separate from and located in the path of movement of said means and moved thereby which determines when the lifter shall release the valve, a speed governor, and a lever actuated by the 120 governor which adjusts one end of the actuator.

6. In a pump, the combination of a shaft, a governor mounted thereon, a sleeve moved by the governor, an eccentric driven by the 125 shaft, a cross-head actuated by the eccentric, a cam on the cross-head, a cylinder, suction and discharge valves therefor, a plunger moved by the cross-head, a lifter for the 130 suction valve that tends at all times to hold

- it open, a device which engages the lifter and the cam, a pivot therefor, and means actuated by the governor sleeve for changing the position of the pivot.
5. 7. In a pump, the combination of a shaft, a governor mounted thereon, a sleeve moved by the governor, an eccentric driven by the shaft, a cross-head actuated by the eccentric, a beveled-faced cam on the cross-head, a cylinder, suction and discharge valves therefor, a plunger moved by the cross-head, a lifter for the suction valve, a device which engages the lifter and causes it to release the valve and is moved by the cam, a crank-10 shaft whose crank supports one end of said device, a lever moved by the governor sleeve, an arm on the shaft, and a connection between the lever and the arm to change the angular position of said crank.
15. 8. In a pump, the combination of a driving shaft, a housing therefor, an eccentric driven by the shaft, a cross-head actuated by the eccentric, a means supported by the housing and forming a guide for the cross-head, a pump casing, devices for attaching the means and casing to the housing, a cylinder in the casing, suction and discharge valves for the cylinder that are contained in the casing, a lifter for the suction valve, 20 an actuator which engages one end of the lifter and also the cross-head, a pivot for the actuator, and means for adjusting the pivot to change the effective action of the cross-head on the actuator and lifter.
25. 9. In a pump, the combination of a casing containing a cylinder, suction and discharge valves therefor, a plunger, a cross-head for actuating the plunger, a cam for the cross-head, a lifter for the suction valve comprising a head, an adjustable stop thereon, a rod attached to the head and extending through the casing and a spring that tends at all times to raise the head and suction valve, a device that extends across one end 30 of the rod and engages the cam at its free end, and an adjustable pivot for the other end of the device.
40. 10. In a pump, the combination of a cas- ing containing cylinders, suction and discharge valves for each cylinder, plungers 50 for the cylinders located side by side, a cross-head that is common to the plungers and to which they are detachably secured, a cam on the cross-head that is located between the plungers, a lifter that is common to all of the suction valves, a device that extends across one end of the lifter into engagement with the cam, and an adjustable pivot for the device.
45. 11. In a pump, the combination of a cylinder, suction and discharge valves therefor, a plunger, a reciprocating member for actuating the plunger, a lifter for the suction valve, an actuator therefor which is moved by the member, a means for adjusting the position of the actuator to change its effect on the lifter, a governor for actuating the means, and a manually-actuated device for modifying the action of the governor on the actuator.
50. 12. In a pump, the combination of a cylinder, suction and discharge valves therefor, a plunger, means for moving the plunger, means for actuating and controlling the suction valve, a speed governor, a connection 75 between the means and the governor which includes an elastic element, and a hand-lever which acts on said means through a lost motion connection.
55. 13. In a pump, the combination of a cylinder, suction and discharge valves therefor, a plunger, means for moving the plunger, a suction valve lifter, a device moving in synchronism with the plunger, a crank-shaft that supports one end of the device, an arm 80 on the shaft, a speed governor, an elastic connection between the governor and said arm, a handle loosely mounted on the shaft and acting on the arm through a lost-motion connection.
60. In witness whereof, I have hereunto set my hand this 21st day of February, 1913.
